UNITED STATES PATENT OFFICE.

LOUIS S. RYSDON, OF CHICAGO, ILLINOIS.

COMBINATION SKYLIGHT AND VENTILATOR.

Application filed October 17, 1923. Serial No. 669,146.

This invention relates to ventilators and more particularly to a combined skylight and ventilator and has for its primary object the arrangement and mounting of ventilating sections which may be swung to a position to give maximum ventilation.

An object of the invention is the pivoting of ventilating sections in a manner that same may be thrown open to ventilate through the entire area thereof.

Besides the above my invention is distinguished in the novel manner of constructing the various frames of movable and stationary sections so as to have interfitting connection to prevent the passage of water or condensation around the sections.

With these and other objects in view the invention will be better understood from the following detailed description taken in connection with the accompanying drawing wherein:

Fig. 1 is a vertical sectional view of a combined skylight and ventilator constructed in accordance with my invention showing one section open and the other closed.

Fig. 2 is an enlarged sectional view through the ridge structure.

Fig. 3 is an enlarged sectional view through the transverse bar construction of the frames.

Fig. 4 is a similar view to Fig. 3 showing the transverse bar construction between two adjacent movable sections.

Fig. 5 is an enlarged sectional view through the curb portion of the frames.

Again referring to the drawing illustrating one of the many constructions of my invention the numeral 1 designates a skylight structure comprising stationary sections 2 and movable sections 3. The movable sections 3 provide the ventilating feature of the skylight. The ridge structure 4 includes downwardly extending edges 5. The pivots 6 of the movable section are arranged under the ridge structure so that the upwardly extending edges 7 of the movable top frame member 8 will move under the ridge structure relative to the downwardly extending edges 5 so that water or condensation will be prevented from passing therearound and drip down into the building.

Referring more particularly to Fig. 3 it will be seen that the frame member 8 of the movable section is further provided with portions overhanging the side wall 8' of a

gutter 10 with a depending U-shaped portion 9 extending into the gutter, said gutter being formed in the side frame portion 11 of the stationary frame 12 that are included in the stationary section structure.

By referring to Fig. 4 it will be seen the side frame portions 11 of the stationary frame are arranged between two companion movable sections 3 and are so positioned that the depending U-shaped portions 9 of companion movable sections will be extended into the gutter 10 when the movable sections are in closed position.

As far as I have proceeded it will be seen that the various movable sections co-act with each other and with the stationary sections in a manner that water or condensation will be positively prevented from passing around the upper edges of the movable sections or between the side edges of the companion movable sections or between the edges of the end movable sections and the stationary frame.

To accomplish the same result with the lower edges of the movable sections I provide the following construction. The curb portion 13 of the lower frame member 13' of the stationary frame carries a trough 14, the wall of which terminates in the flange 15. The movable bottom frame 8^a is so arranged that when it is in closed position its horizontal portion 8^b is seated in the trough 14. The horizontal portion 8^b has a laterally extending edge which terminates in the downwardly extending lip 16. The lip 16 overhangs the flange 15, thus producing the desired result.

Any suitable mechanism may be used for raising the movable sections such as shown at 17. This mechanism includes a rack bar 18 hinged to the movable sections as indicated at 19.

From the foregoing description taken in connection with the accompanying drawing it will be apparent that I provide a combination skylight and ventilator wherein the maximum amount of ventilation can be accomplished and in such a manner that dripping of water into the building is positively prevented.

It will also be noted the parts are substantially connected and associated and the movable sections may be readily raised.

It is, of course, to be understood that the invention may be constructed in various other manners and the parts associated in

different relations and, therefore, I do not desire to be limited in any manner except as set forth in the claim hereunto appended.

Having thus described my invention what I claim is:

A skylight structure including a stationary frame comprising a sheet metal member including a vertically extending section having a portion bent outwardly therefrom at an acute angle to said vertical section, the outer portion of said outwardly bent portion being bent upwardly at right angles to the main extent thereof and the edge portion thereof being bent outwardly so as to be dis-

posed parallel to said main extent, and a movable frame disposed when in closed position to have the edge portion thereof in the main extent of said outwardly bent portion of said main frame and including members providing a lip adapted to rest on said parallelly disposed edge portion of the stationary member, the outer edge of said lip being bent downwardly at right angles to the main extent thereof and disposed parallel to said right angularly extending portion of said stationary member.

In testimony whereof I affix my signature.

LOUIS S. RYSDON.
